UNITED STATES PATENT OFFICE.

OSCAR HAMMERSTEIN, OF NEW YORK, N. Y., ASSIGNOR TO MALVINE HAMMERSTEIN, OF SAME PLACE.

CIGAR-MACHINE.

SPECIFICATION forming part of Letters Patent No. 244,453, dated July 19, 1881.

Application filed April 28, 1881. (No model.)

To all whom it may concern:

Be it known that I, OSCAR HAMMERSTEIN, of New York, in the county and State of New York, have invented an Improved Machine for 5 Making Cigars, of which the following is a specification.

Figure 1 is a side elevation of my improved machine for making cigars. Fig. 2 is a detail vertical central section through the lower part 10 of the feed-hopper. Figs. 3, 4, and 5 are detail face views of the cams for actuating the slides in the hopper, the valve in the air-pipe, &c. Fig. 6 is a detail top view of portion of the air-pipe. Fig. 7 is a face elevation of the machine. Fig. 15 8 is a detail vertical transverse section of the lower part of the feed-hopper and longitudinal section of the receiving-chamber, which is charged by said hopper. Fig. 9 is a vertical section through the end of the receiving-chamber and through the jointed and vertically-reciprocating receiving-mold. Fig. 10 is an elevation of the side which is opposite to that shown in Fig. 1. Fig. 11 is a sectional view, 20 showing the receiving-mold discharging into the intermediate mold and the latter into the main cigar-mold. Fig. 12 is a side view of the intermediate mold. Fig. 13 is also a side view of the intermediate mold, showing it connected with the operating mechanism. Fig. 14 is a 25 detail horizontal section on the line *c c*, Fig. 11. Fig. 15 is an enlarged vertical longitudinal section of the intermediate mold; Fig. 16, an enlarged detail cross-section of one of the chambers thereof. Fig. 17 is a top view of one 30 of said chambers, and Fig. 18 a bottom view thereof. Figs. 19, 20, and 21 are detail cross-sections of the intermediate mold, showing it in different positions with reference to the main cigar-mold.

40 This invention relates to several improvements in machinery for forming tobacco into fillers for cigars, and for covering such fillers in an appropriate mold with a leaf of tobacco, commonly known as the "binder."

45 The invention comprises a new arrangement of parts for conveying the tobacco from a hopper into a chamber, which I term the "receiving-chamber," and thence into a receiving-mold; a new arrangement of said receiving-chamber, 50 whereby the tobacco is prevented from clogging in the outlet therefrom; a new mechan-

ism for conveying the portions of tobacco that remain in the receiving-chamber back into the hopper; a new combination of parts or an intermediate mold for transferring the filler from 55 the receiving-mold to the main cigar-mold, said intermediate mold being provided with mechanism for receiving and applying the binder, and other features of improvement which are hereinafter more fully described. 60

As to the hopper, I provide the same with two plungers, one reciprocating in a vertical, the other reciprocating in a horizontal, direction, so that by means of these plungers the charge of the desired extent may in the proper 65 manner be deposited in the receiving-chamber, with which and with the receiving-mold said hopper is combined. The receiving-chamber is provided with a rotating finger or fingers for disturbing the tobacco, so as to prevent it clogging, and the receiving-mold is attached to a frame which, when the said receiving-mold is in its lowermost position, carries a pipe in line with the receiving-chamber to permit the tobacco which is still in the receiving-chamber to be forced through said pipe 70 back to the hopper. The receiving-mold discharges into an intermittently-rotating intermediate mold, which has four (more or less) 75 distinctive mold-cavities, each of which has a 80 sliding bottom and a folding cover, for the purposes hereinafter specified.

The invention also consists of other details of improvement and combinations of parts, as 85 hereinafter more particularly stated.

In the accompanying drawings, the letter A represents the frame of the machine. In this frame is hung the main operating-shaft B, which is revolved in the direction of the arrow shown in Fig. 10 by suitable mechanism. On 90 the table C, which is supported by the frame A, rests the supporting-bracket *a* of the "receiving-chamber" D, as I term it, and above this receiving-chamber is secured upon it the hopper E. In Fig. 2 the lower part of this hopper, 95 in its relation to the receiving-chamber, is more clearly shown, also in Fig. 8. It will be seen that the receiving-chamber D has an inlet-opening at the side, which opening can be closed by means of a horizontally-sliding plunger, F, 100 which plunger moves below an opening, *b*, in the bottom of the hopper E, above which open-

ing is a vertically-reciprocating plunger, G. The tobacco is put in the hopper E when the plunger G is lifted and the plunger F brought below the opening *b* in the bottom of the hopper, as shown by full lines in Fig. 2. A vibrating scoop, H, is then moved in the hopper from the position shown in full lines in Fig. 2 to the position shown in dotted lines in Fig. 2, and sweeps a certain quantity of tobacco into the opening *b* upon the slide F and below the plunger G. The plunger G is thereupon moved down, and at the same time the plunger F is moved away from the receiving-chamber D, so that the charge of tobacco will, by the plunger G, be deposited in front of the horizontal plunger F, between the same and the chamber D. Finally the horizontal plunger F is moved toward the chamber D and crowds all the tobacco that constitutes the charge into the receiving-chamber D. By this means I am enabled to supply the receiving-chamber with the necessary charges from time to time, and also to have it properly sealed against the escape of air through the inlet-opening, so that the tobacco may subsequently be blown from the receiving-chamber into the receiving-mold I by a blast of air or other gas. Were it not for these two plungers and the arrangement shown, it would be very difficult not only to measure the charge of the tobacco, but also to properly seal the receiving-chamber so as to prevent the air that is blown into it from passing out through the crevices or through the opening by which the tobacco entered it, instead of affecting the tobacco for filling the receiving-mold in the manner desired.

The scoop H, plunger G, and plunger F are moved by the following mechanism:

The scoop H is mounted on a shaft which at its end carries a crank, d, as shown in Fig. 1, and which, by a rod, e, connects with a link, f, which, by a cam, g, that is mounted upon the shaft B, receives vibratory motion in one direction, and by a suitable spring, h, in the opposite direction, so that thus the rotation of the shaft B causes the scoop H to be gradually moved, when the cam g touches the link f, toward the path of the plunger G, and afterward to be suddenly withdrawn by the spring h from said path and returned to its normal position, which is shown by full lines in Fig. 2.

The vertically-reciprocating plunger G is attached to a rod, i, which extends through a vertical slot of the hopper, as indicated in Fig. 1, and connects by a suitable rod, j, with a lever, k, that is pivoted to the frame A, said lever being connected by another rod, l, with a tappet, m, that is vibrated by the cam g of the shaft B, as indicated in Fig. 4. A suitable spring, n, serves to raise the lever k and the slide i and plunger G as soon as the cam g is out of contact with the tappet. It will be seen that by this arrangement the cam g first depresses the lever f so as to swing the scoop H into the dotted position shown in Fig. 2, and immediately afterward causes the tappet to be

moved downward and the slide G to descend in manner described.

The horizontal slide F connects by a link, o, with a bell-crank, p, from which a rod, q, extends to a lever, r, that carries a friction-roller, s, that is in contact with the edge of a cam, t, which is mounted upon the shaft B. This cam, which is more clearly shown in Fig. 3, has a circular edge with a large radius, another circular edge with a small radius, and curves that join these two parts in its circumference, so that when the friction roller or pin s is in contact with the small curve that is concentric to the shaft B, as in Fig. 3, the rod q will be drawn down and the plunger F withdrawn from under the opening *b*, as indicated by dotted lines in Fig. 2; but when the pin s is in contact with the larger circle of the cam t the plunger F will be moved toward the chamber D and beneath the opening *b*, as shown by full lines in Fig. 2. These operations of the two plungers above described are so timed that when the slide G is down in its lowermost position the slide F is away from beneath the opening *b*, the position of both said parts being as shown by dotted lines in Fig. 2; but when the plunger G is raised, the cam q having left contact with the tappet m, the larger part of the cam t comes beneath the pin s, as in Fig. 1, and lifts the rod q, causing the plunger F to move into the position which is shown by full lines in Fig. 2.

The chamber D has two openings, as shown in Fig. 8. One of these openings is the discharge-opening, and communicates with the interior of the receiving-mold I, as in Fig. 9, whereas the other opening of the receiving-chamber communicates with a pipe, J, that connects in suitable manner with a blowing apparatus, through which a violent current of air can at any desired time be blown into the receiving-chamber D. This pipe J, I term the "air-pipe." In it is a suitable valve for obstructing or permitting the passage of the air, as may be desired. This valve is fitted upon a spindle that carries a crank, u, (see Fig. 6,) and this crank connects by a rod, v, (see Fig. 1,) with a lever, w, that rests upon a disk, x, which is mounted upon the shaft B, and more clearly shown in Fig. 5, and which has two projecting toes. Whenever one of these toes arrives under the lever w it elevates the same and causes the valve in the air-pipe J to open. Whenever the toe recedes from under the lever w the latter drops and causes the valve to close. I have so arranged the position of these toes on the disk x with reference to the cams g and t that the valve in the pipe J will be suddenly opened to allow a sharp jet of air to be passed into the chamber D as soon as the plunger F assumes the position which is shown in Fig. 2 by full lines, thereby discharging the contents of the chamber D into the mold I, which at that time is in line and communication with the chamber D, as shown in Fig. 9. The mold I, being now charged with tobacco, descends, being moved downward by

the instrumentalities f^2 , g^2 , and h^2 , hereinafter described, and when in its lowermost position a pipe, L, which is attached to the head y of the mold I, arrives in line with the discharge-opening of the chamber D, and at that time the next toe of the cam x causes the valve to be opened and another jet of air to be blown into and through the chamber D and pipe L. The pipe L enters the upper part of the hopper E, as shown in Fig. 7, and by the means last described, whatever tobacco remains in the chamber D after the mold I is filled will re-enter the hopper E, and will therefore neither be wasted nor remain in chamber D to be in the way of the next succeeding charge.

It will be perceived from the foregoing that the chamber D receives two charges of air, while the plunger F, that charges it with tobacco, closes its tobacco-supply opening, the first charge of air serving to feed the supply-mold I, the next charge of air serving to discharge the remnants of tobacco through the pipe L back into the hopper E.

The receiving-mold D, in order to prevent the clogging of tobacco therein under the influence of a violent current of air that is blown into it, is provided with rotating stirring apparatus which is composed of one or more wires or blades, a^2 , that are mounted upon a shaft, b^2 , that is hung in pipe J, as in Fig. 8, or otherwise so hung as to be capable of revolving the wires a^2 within the chamber D. These wires may either be of ordinary curved form, such as indicated in Fig. 8, or they may be S-shaped or of other suitable form. They are revolved by revolving the shaft b^2 through a belt, c^2 , that passes around a suitable pulley on the shaft B. The wires a^2 , rotating within the chamber D, keep the leaves of tobacco that are fed into said chamber duly separated from each other, so that they may all be blown in proper manner by the air into the receiving-mold I, whereas without such arms or wires there would be danger of clogging the discharge-opening of the chamber D with tobacco when the air was blown into said chamber.

The receiving-mold I is a jointed mold, composed of three pieces—to wit, a central piece, d^2 , and two wings, e^2 , as clearly shown in Fig. 11, and on a still larger scale in Fig. 19. This mold I is attached to a head or vertically-reciprocating carrier or slide, y, which is part of a reciprocating framing, f^2 , that receives up-and-down motion by rod-connection g^2 with an eccentric, h^2 , that is mounted upon the shaft B, so that by the rotation of the shaft B the frame f^2 is moved up and down, and with it the carrier or slide y and the mold I, that is attached thereto, likewise the pipe L, of which the lower end joins the carrier y. The mold I is fitted upon a suitable dovetail-formed or other projection of the head y, so that said mold can be taken off the head y and another mold of a different size or form be substituted in its place, thereby enabling me to make on the machine cigars of different sizes and forms.

A suitable catch, i^2 , (shown in Fig. 9,) serves to lock the mold I to the head y. As the mold I is carried down away from the chamber D pins that project from the wings e^2 , and that enter curved grooves j^2 in the stationary part of the machine, (see Figs. 10 and 11,) are in said grooves moved outward, so as to cause the wings e^2 to open at the proper time, permitting the central portion, d^2 , of the mold I to force the contents of said mold into the intermediate mold, M, as indicated in Fig. 11 and also in Fig. 19.

The intermediate mold, M, is a structure of entirely original and peculiar kind, which I will now endeavor to describe. Around a stationary circular plate, or rather pair of plates, k^2 , (see Fig. 15,) is placed a cylindrical shell, l^2 , which is capable of revolving around the disks k^2 and held in place thereon, and which carries four (more or less) removable "mold-chambers" or "cigar-chambers," as I may term them, which are marked m^2 in the drawings. Each of these chambers m^2 is formed of two rigid side plates and of a vertically-movable bottom plate, n^2 . Such bottom plate is in each mold-chamber, by springs o^2 , drawn inward, or toward the axes of the disks k^2 , so that normally and under the influence of its springs o^2 each slide n^2 will be in a position to form part of the chamber m^2 to which it may pertain. Intermittent rotary motion in the direction of the arrow shown in Figs. 11 and 12 is imparted to the shell l^2 , and thereby also to the mold-chambers m^2 , which are carried by the same. The mechanism for imparting such intermittent rotary motion to the shell l^2 is, by preference, a bell-crank lever, p^2 , (see Fig. 10,) connected by link to a lever, q^2 , that is by a spring, r^2 , held in contact with the edge of a cam, s^2 , that is mounted upon the shaft B. A pawl, t^2 , is pivoted to the bell-crank p^2 , and catches into proper projections of the shell l^2 . When the lever q^2 is in contact with the larger portion of the peculiarly-formed cam s^2 , as in Fig. 10, its pawl will be vertically above the axis of the shell l^2 . In this position, which is the position shown in Figs. 10 and 11, the ring l^2 will remain as long as the lever q^2 is in contact with the larger circle of the cam s^2 , but as soon as the lever q^2 is by the spring r^2 , during the rotation of the shaft B, brought against the smaller circle of the cam s^2 the pawl will be drawn down into contact with the projection or tooth that is at the right-hand side of the ring l^2 , as shown in Fig. 13, and will take hold of the next projection or tooth, remaining stationary, however, as long as the lever q^2 is virtually in contact with the small circle of the cam s^2 , as shown in Fig. 13. As soon as the lever q^2 is pushed off this smaller circle by the nose of cam s^2 (see Fig. 13) the pawl is lifted, and the cylinder l^2 thereby turned in direction of the arrow shown in Fig. 12 to the extent of ninety degrees, thereby bringing a new mold-chamber m^2 under the reciprocating-mold I and carrying the filled mold m^2 , that was for-

merly under I, to the left-hand side, for discharge into the main cigar-mold N, that is placed there for the reception of the contents of the mold-chambers m^2 . I have shown four 5 mold-chambers m^2 on the intermittently-rotating mold M; but their number may be varied at pleasure, in which case the stroke of the pawl t will also be proportionately varied, so as at each movement to bring an empty 10 mold-chamber under the reciprocating mold I. In each of its several positions the mold-ring l^2 , with its chambers, is locked by a locking-bolt, u^2 , (see Fig. 12,) that moves along one of the plates h^2 , and springs, under the influence 15 of a suitable spring, into a notch, x^2 , of the ring l^2 as soon as such notch arrives in line with the bolt. This bolt is also shown in its locked position in Fig. 15. When the pawl is 20 swung down to take hold of a new tooth of the cam—a cam-edge on the hub v^2 of the bell-crank p^2 —bears against a lever, w^2 , that engages a projection of the bolt u^2 and draws the bolt out of the notch of the ring l^2 , so as to permit the turning of the ring l^2 by means of the 25 pawl, in manner stated. There are as many notches in the inner edge of the ring l^2 as said ring is provided with mold-chambers. These notches are shown at x^2 in Fig. 12, and each of them in turn receives the bolt u^2 . 30 It will be readily understood that as the reciprocating mold I, containing a charge of tobacco, approaches the mold-chamber m^2 , which is directly beneath it, (the wings e^2 opening,) the contents of the mold I are deposited 35 into said mold-chamber m^2 in manner clearly indicated in Figs. 11 and 19. It will also be readily understood that when afterwards the mold I is lifted out of the mold-chamber m^2 and the ring l^2 , carrying such mold-chamber, is 40 turned the contents of said mold-chamber can be brought in line with the proper cavity of the main cigar-mold N, which is placed in a vertical position in a suitable carrying chamber or clasp, O, opposite the intermediate mold 45 M, as shown in Fig. 11. Springs a^3 , bearing against the back of the mold N, crowd it against the front edges of its containing-chamber O (see Fig. 14) and hold it stationary, yet allowing it to be moved downwardly, in manner 50 hereinafter described. As soon as the mold-chamber m^2 , which contains its charge of tobacco, arrives opposite and in line with a cavity of the main cigar-mold N, the bottom n^2 of said mold-chamber m^2 is moved toward the 55 mold N far enough to push the contents of such chamber into the appropriate cavity of the main cigar-mold. This is clearly indicated in Figs. 11 and 21. Thus the charges that are originally deposited within the reciprocating 60 mold I are transferred to the main cigar-mold N. This main cigar-mold receives rectilinear motion intermittently by projecting noses b^3 , that are on the sides of the mold-chambers m^2 and engage in recesses c^3 that are cut into the 65 mold N, as is more clearly shown in Fig. 21. In this figure the mold N is shown in position

for receiving a charge from one of the mold-chambers m^2 by the outward motion of the bottom n^2 of said chamber, the nose b^3 being in its proper recess c^3 . Now, after the mold-chamber m^2 has been emptied and rotation of the ring l^2 in the direction of the arrow is resumed, the nose b^3 will move the mold N down a little way, sufficiently far to bring the recess c^3 , which is next above the cavity last 70 filled with tobacco, into the path of the next succeeding nose b^3 , that is on the mold m^2 , which next moves toward the cigar-mold N to deposit its charge into the latter. The bottom n^2 of each mold-chamber is moved outward 75 for discharging the contents of the mold-chamber by means of a sliding bolt, d^3 , which is held in appropriate guides e^3 , that connect the stationary disks k^2 . (See Fig. 15.) The bolt d^3 , or pair of bolts, two being shown in Fig. 15, 80 for moving each bottom n^2 , receive their motion from cranks f^3 of a shaft g^3 , that is hung in the disks k^2 . This crank-shaft g^3 connects with a lever, h^3 , that is tilted at the proper time by a pin, i^3 , on the cam s^2 , so as to vibrate 85 it and move the bolts d^3 in proper manner. After having been thus moved outward to discharge the contents of the mold-chamber m^2 , the spring o^3 draws the bottom n^2 back into its normal position, and is assisted in this by 90 another spring, j^3 , that is attached to the lever h^3 , in manner indicated in Fig. 10. The bolts d^3 should not be quite as long as the diameter of the disk k^2 , so that in their normal position, when they are not active, they will not interfere with the motion of the ring l^2 around the disks k^2 . The normal position of a bolt d^3 is 95 clearly shown in Fig. 19. 100 I have already shown what becomes of the charge of the mold I, that is forced out of the chamber D, and that the contents of the chamber D are successively in proper form placed into the cavities of the main cigar-mold N. It only remains to show how I apply the binder or covering-leaf of tobacco to and around the 105 filler or inner portion of the cigar. That part of the tobacco that is blown from the chamber D into the mold I is the filler. The mold I contains, therefore, only the filler; but before that 110 filler is deposited in the proper mold-chamber m^2 of the intermediate mold, M, a leaf of tobacco, which is to form the binder, is placed over and across the mold-chamber m^2 , as shown in Fig. 11. This leaf is bulged or bent down by the 115 filler, which the mold I forces into said mold-chamber m^2 , as shown in Fig. 19, and its two ends—that is to say, the two ends of said binder—project beyond the two sides of the mold-chamber after the mold I has been lifted off the latter. On its way to the main mold N 120 the mold-chamber m^2 thus filled is brought beneath a swinging cap, P, which folds one end of the binder over the filler. (See the dotted position in Fig. 11.) The cap P is a sheet-metal or other plate, properly curved and pivoted to one side of the mold-chamber m^2 , to 125 which it pertains. It is moved at the proper 130

time by having an extension or tail-piece, k^4 , come in contact with a stationary projection, k^3 , that is supported by the cross-bars e^3 . (See Figs. 15 and 20.) After leaving contact with this projection k^3 , the cap P is drawn off the mold-chamber by a suitable spring, b^3 . While the cap P still holds one end of the binder on the filler, the mold-chamber, in its motion toward the main cigar-mold N , arrives under a stationary blade, m^3 , (see Figs. 20 and 21,) that is rigidly secured in the frame-work of the machine, and with which the loose end of the binder comes in contact so as to be folded over the cap P , as clearly shown in Fig. 20. It is when the two ends of the binder have been folded that the spring b^3 withdraws the cap from the face of the chamber m^2 , leaving the binder on the filler in proper position to be inserted into the cavity of the main cigar-mold N .

I have now faithfully described the entire operation of my machine and all those parts thereof which I deem to be necessary; but it is quite clear, and I desire it to be particularly understood, that many of the details of the invention may be varied without materially departing from the spirit thereof.

Instead of the mechanism for imparting motion to the different portions of the machinery which I have described, other mechanism may be employed, the proportions of the parts may be varied; but the main feature of my invention can still be retained by so varying the proportions, operating mechanism, or immaterial details. I have said that the cap P is pivoted to the mold-chamber m^2 ; but I prefer not to pivot it directly to said mold-chamber, as it is wiser to employ a connecting-link, n^3 , (see Fig. 12,) so as to give to the cap not only the vibrating but also a sort of lifting movement, which will carry it clear of the mold-chamber m^2 , over which it is to move.

I claim—

1. The combination of the scoop H , and its crank d , and link e , lever f , cam g , and the slide G , and the connections thereof, with the tappet m , all arranged so that the cam g will move the scoop and the slide G in succession, substantially as specified.

2. The combination of the hopper E , receiving-chamber D , and air-pipe J with the charging-plunger F and mold I , and with mechanism, such as described, for twice opening the valve of the air-pipe while the chamber D is closed by the plunger F , so as to permit the charge of the chamber first to be blown into the mold I and the remnants next into the hopper E , substantially as described.

3. The vertically-reciprocating receiving-mold I , in combination with the chamber D and with the air-pipe J , and with the vertically-reciprocating pipe L and hopper E , for operation substantially as specified.

4. The air-pipe J , leading into the chamber D , in combination with a valve and with the mechanism u , v , w , and x for opening said valve twice, and with the slide F , substantially as herein shown and described.

5. The combination of a receiving-chamber, D , of a cigar-mold with the air-pipe J and with the rotating wire or wires a^2 , arranged within said chamber D , substantially as described.

6. The combination of the receiving-mold I with the intermediate mold, M , and main cigar-mold N , all arranged for operation substantially as described.

7. The mold-chamber m^2 , combined with the swinging cap P and fixed blade m^3 , and with mechanism for rotating the mold and swinging the cap, substantially as described.

8. The combination of the mold-chamber m^2 on the ring l^2 with the hinged cap P , spring b^3 , and stationary projection k^3 for moving the cap, substantially as specified.

9. The flat-bottomed main cigar-mold N , constructed with the receiving-cavities that are closed at the bottom, and with the recesses or notches c^3 on the same side on which it has the receiving-cavities, and between the same, for the purpose of being moved by the intermediate mold, M , that faces it, substantially as described.

10. The combination of the intermediate mold, M , with mechanism for imparting intermittent rotary motion to it, and with the projecting noses b^3 , and with the main cigar-mold N , having notches c^3 , substantially as described.

11. The intermittently-rotating ring or cylinder l^2 , carrying mold-chambers m^2 , in combination with mechanism for moving it, and with the bolt u^2 for locking it in its terminal positions, and with the lever w^2 for unlocking it, substantially as described.

12. The main cigar-mold N , placed in a housing, O , and held there by friction-springs a^3 , in combination with the rotating mold M , which is provided with means for moving the main cigar-mold N , and with a plunger or plungers for discharging its contents into the cavities of the main cigar-mold N , substantially as specified.

13. The combination of the mold-chamber m^2 , having a movable concave-faced bottom, n^2 , and spring o^2 , and secured on rotary ring l^2 , with the inner fixed frame, e^3 , reciprocating slide d^3 , crank f^3 , and oscillating crank-shaft g^3 , for operation substantially as herein shown and described.

The foregoing specification of my invention signed by me this 23d day of April, 1881.

OSCAR HAMMERSTEIN.
